LAVATORY FLUSH VALVE

Filed Oct. 4, 1947

FIG. 1

UNITED STATES PATENT OFFICE

2,471,662

LAVATORY FLUSH VALVE

Joseph Sweeney, Auburn, N. Y.

Application October 4, 1947, Serial No. 778,009

4 Claims. (Cl. 137—93)

1

This invention relates to lavatory flush valves and more particularly to a valve construction adapted, when operated, to close automatically after a predetermined interval of time.

One of the objects of the present invention is to provide a flush valve in which the period of operation may be accurately and conveniently adjusted and controlled.

Another object is to provide such a valve which will pass the maximum amount of water during a predetermined operating period.

Still another object is to provide a self-closing flush valve which will permit full-capacity flow throughout substantially the entire period of operation.

Another object is to produce such a valve which is reliable in operation, economical in construction, and which may be readily installed, if desired, in existing structures as a replacement for the usual flush tanks in office buildings, dwellings, and the like, without necessitating extensive changes in plumbing.

Still another object is to provide a self-closing flush valve operable from supply conduits of relatively small diameter.

Other objects and advantages will hereinafter appear.

In accordance with the present invention I provide a self-closing lavatory flush valve adapted to be opened by a manual lever and so constructed and arranged that it will be retained in its fully opened position for the entire flushing period. At the end of such period the valve closure member is released automatically and caused to move smoothly and rapidly to its fully closed position. Suitably adjustable timing means is provided for regulating the total period of operation, independently of normal variation in the length of time the manual lever is held operated.

By virtue of the wide open condition of the valve throughout the flushing period, the full available water supply flows continuously until the moment of closing, thus resulting in a large total flow during a given flushing cycle. With the same available inlet capacity, substantially twice the outlet volume will be obtained with the valve of the present invention as is obtainable with the usual form of self-closing valve in which the valve member is fully open only at the start of the flushing period, and thereafter slowly progresses to the fully closed position. Otherwise expressed, the valve of the present invention, with its sustained full capacity flow, requires a much lower rate of flow in order to pass the same amount of water during a given flushing

2

period, than the maximum rate of flow required with the gradually closing type of valve. The valve closure member and associated parts, therefore, may be of somewhat smaller size and/or of shorter stroke, and the valve may be satisfactorily operated in a system employing smaller supply conduits. As a matter of fact, under normal pressure conditions, the valve may be suitably operated from the usual half or three-quarter inch water pipes employed in the usual type of dwellings and, therefore, may replace the ordinary flush tanks in existing buildings or be used in place thereof in new construction while permitting the same economy in the size of the supply conduits.

The construction and operation of my improved valve will best be understood by reference to the drawing, in which:

Fig. 1 is a vertical sectional view of a flush valve 20 constructed in accordance with a preferred embodiment of the invention;

Fig. 2 is a horizontal sectional view taken on the line 2—2 of Fig. 1;

Fig. 3 is a horizontal sectional view taken on the line 3—3 of Fig. 1;

Fig. 4 is a fragmentary vertical sectional view taken on the line 4—4 of Fig. 1; and

Fig. 5 is a bottom view of the valve lifting and vacuum retaining member, indicated generally by the reference character A in Fig. 1.

Referring to the drawing, the valve mechanism comprises an outer cylindrical casing 10 having disposed therein an inner eccentrically disposed cylindrical valve enclosing casing 11 and 35 a float enclosing cylinder 12. The casing 10 is closed at the upper end by a dome-shaped cover 13 into which the casings 11 and 12 open. The cover 13 is removably secured in place by screws 14.

40 The casing 11 is closed at the lower end by a cap 15 and casing 12 is closed by a plug 16. The space intermediate the casing 11, 12 and casing 10 is closed at the lower end by a bottom wall 17.

An inlet passageway 18 having a flanged end 45 19 extends horizontally through the casing 12 into the casing 11 and forms a seat for a float 21 contained within the casing 12. The passageway 18 terminates in an annular chamber 22 formed between the wall of casing 12 and a cylindrical chamber 23 defined by the vertical cylindrical wall 24 and walls 25 and 26. The chamber 23 is retained concentrically within the chamber 11 by upper and lower web members 27 and 28, 55 respectively, and a flaring extension 29 into which

the top, bottom and side walls of the chamber merge and form the outlet passageway 31.

Valve seat inserts 32 and 33 are suitably threaded into the upper and lower members 27 and 28 upon which the integral valve members 34 and 35 are adapted to seat. A closure disk 36 is threaded into the chamber 11 above the valve closure member 34 and in turn has threaded thereinto a packing gland comprising the associated plug 37, cap 38, and packing material 39.

A valve stem 41, suitably connected to the valve closure assembly, passes through the gland and is threaded into the bottom of the valve lifting member A. This member comprises a flat disk portion 42 having depending spaced ears 43, 44 and a bridging web 45, into the latter of which the valve stem is secured. A port 46 is provided in the disk portion 42 between the depending ears, this port being normally closed by a conical closure member or valve 47 carried by a lever 48 pivoted on a pin 49 threaded through one of the depending ears 43. The lever 48 extends through a slot 50 in the tubular float casing 12 and terminates in the upward path of the float 21.

Disposed above the disk 42 is a vacuum cup member 51 of convex shape and of suitable resilient material, such as rubber, adapted to grip the disk 42 and hold it by suction when the latter member is raised into contact therewith. The vacuum cup 51 is supported directly above the disk 42 by a bracket 52.

An operating lever 53 is pivoted on a pin 54 carried by lugs 55 formed on the outer wall of the enclosing casing. The lever 53 extends into the casing 11 and has the bifurcated end 56 thereof extending about the valve stem 41 beneath the web portion 45 of the valve lifting member A.

A bleed passageway 57 extends from the lower end of chamber 23 into the tubular casing 11, this passageway being formed in part in the wall of the casing and in part in a valve insert 58 threaded into the interconnecting wall. A needle valve 59 adjustably mounted in a plug 60 is arranged in axial alignment with the passageway 57 to control the flow of water therethrough. The float 21, contained in the tubular casing 12 may consist of a hollow body of thin corrosion-resistant metal or other material of a buoyant nature. It is provided with an upper conical face 61 adapted to engage with a valve seat 62 threaded into the casing 12.

The operation of the valve is as follows: In the normally closed position of the valve with the valve closure members 34 and 35 resting on their respective seats, the water in the float casing 12 will be below the level of the inlet passageway and the float 21 will be resting upon the upper wall of this passageway. Upon the manual depression of the lever 53 the valve lifting member A will be raised, thereby lifting the closure members 34 and 35 to open position and bringing the disk 42 into gripping contact with the vacuum cup 51, by which the valve assembly will be retained in its uppermost or fully opened position. Water will then flow at full capacity from the supply conduit through the inlet passageway 18, and the upper and lower valve ports, and will be discharged through the outlet passageway 31.

A small regulated amount of water will bleed through passageway 57 into the float chamber 12 to raise the float 21 until, after a predetermined interval, it engages lever 48 to trip the same, opening the valve 47 and breaking the vacuum in the cup 51, whereupon the disk 42

is suddenly released, permitting the valve assembly to drop by gravity to bring the valve closure members to their seats. The seating of the valve may be facilitated by making the area of the upper closure member 34 of somewhat greater area than the lower member 35.

As soon as the valve members are seated, water from the float chamber 12 drains through the passageway 57 permitting the float 21 to drop to its normal position.

The interval during which the valve is retained in its open position may be varied by suitable adjustment of the needle valve 59, this period starting the instant the valve is operated and being independent of any normal variations in the length of time the lever 53 is held depressed. Therefore, unless the lever is held operated for an abnormally long period, the flushing period is always constant and may be adjusted to the most economical period. In case of a prolonged depression of the lever 53 the float 21 will, immediately after opening of the vacuum valve 47, engage the valve seat 62 to prevent water from rising further in the tube 12 and overflowing into the upper chamber.

The valve is also compensating for line pressure since the rate of flow through the valve outlet 31 and through the bleeder passage 57 are both equivalent functions of the line pressure. Therefore, should the line pressure increase or decrease for any reason, the period of operation will be automatically shortened or lengthened to give approximately the same total flow.

As heretofore stated, the valve assembly is retained in its fully opened position until released by the float 21, after which it drops quickly and smoothly to its seat, thus giving full flow characteristics to the valve throughout the full flushing period. The inlet conduit 18 and associated supply pipes, therefore, may be of materially smaller diameter than in the case of flush valves which are open to the maximum capacity only at the start of the flushing cycle and which therefore require a relatively large initial flow. This characteristic permits the present valve to be employed in many existing installations where the water pressure or the supply conduit size is considered insufficient to operate the usual type of flush valves.

Obviously, many changes may be made in the construction of the valve without departing from the essential characteristics thereof, and I contemplate all such changes as coming within the scope of the appended claims.

What I claim is:

1. A flush valve comprising a casing having an inlet port, an outlet port and a passageway therebetween, a valve seat in said passageway, a valve closure member normally resting on said seat and closing said passageway, means for moving said closure member from its seat to open said valve, vacuum means operative upon said movement for retaining said closure member from its seat and means operable by fluid passing through said passageway for breaking said vacuum to release said valve closure member to close said valve.

2. A flush valve comprising a casing having an inlet port, an outlet port and a passageway therebetween, a valve seat in said passageway, a valve closure member normally resting on said seat and closing said passageway, means for moving said closure member from its seat to open said valve, a vacuum cup member, means carried by said closure member adapted to be brought into

vacuum gripping relation with said vacuum cup member upon said movement to retain said closure member from its seat and means operable by fluid pressure through said passageway for breaking said vacuum to release said valve closure member to close said valve.

3. A flush valve comprising a casing having an inlet port, an outlet port and a passageway therebetween, a valve seat in said passageway, a valve closure member normally resting on said seat and closing said passageway, means for moving said closure member from its seat to open said valve, a vacuum cup member, means carried by said closure member adapted to be brought into vacuum gripping relation with said vacuum cup member upon said movement to retain said closure member from its seat and timed delay means acting after a predetermined in-

terval for breaking said vacuum to release said valve closure member to close said valve.

4. A flush valve comprising a casing having an inlet port, an outlet port and a passageway therebetween, a valve seat in said passageway, a valve closure member normally resting on said seat and closing said passageway, means for moving said closure member from its seat to open said valve, a vacuum cup member, means carried by said closure member adapted to be brought into vacuum gripping relation with said vacuum cup member upon said movement to retain said closure member from its seat, a float actuated by fluid passing through said passageway and valve means operated by said float for breaking said vacuum to release said valve closure member to close said valve.
